UNITED STATES PATENT OFFICE.

MARTIN FISCHER, OF ZURICH, SWITZERLAND, ASSIGNOR TO FISCHER MOTOR CORPORATION, A CORPORATION OF NEW YORK.

METHOD OF MAKING ENGINE-CYLINDERS.

1,117,653.

Specification of Letters Patent. Patented Nov. 17, 1914.

Application filed June 8, 1914. Serial No. 843,653.

To all whom it may concern:

Be it known that I, MARTIN FISCHER, a citizen of Switzerland, a resident of Zurich, in the Canton of Zurich, Switzerland, have 5 invented certain new and useful Improvements in the Method of Making Engine-Cylinders, of which the following is a specification, reference being had to the accompanying drawings, made a part hereof.

10 My invention relates to the method of making engine cylinders and more particularly to the bore of the same, and providing valve seats in the walls of the cylinders.

15 Among other objects, my method affords extreme accuracy with the minimum of expense.

In a particular form of engine where my method is especially applicable, the engine cylinder has a longitudinal recess in the side, 20 opening into the cylinder, in which recess a valve is located and reciprocates longitudinally. In a prior application filed by me January 12, 1912, I show a cylinder with integral head. A further development of that 25 type of engine embodied a detachable head so that the main cylinder casting is open at both ends and therefore permits boring tools to be put through the cylinder and supported close to each end. In this case I provide 30 for the boring of the valve recesses as hereinafter described, with reference to the drawings forming a part hereof, in which:

Figure 1 is a plan of the top of a cylinder. Fig. 2 is a vertical section of the main cylinder casting. Fig. 3 is a vertical section of one end of a cylinder. Fig. 4 is a vertical section of part of a cylinder showing the removable cylinder head in position.

35 In the drawings, A is the cylinder casting; B the removable cylinder head; C is the portion of the cylinder wall concentric with the piston; D—D are grooves running longitudinally of the cylinder and may be either one or more, depending upon the number of 40 slide valves of this character to be used in the design; E is a temporary web; E' is a temporary frame.

I will now describe my method of machining cylinders with reference to the particular form shown in the drawings, which is a 45 design of cylinder made to use slide valves reciprocating along the inner side of the cylinder wall and having a crescent cross-section. In this form the main cylinder casting 50 requires longitudinal recesses or grooves

in the inner wall running the length of the main cylinder casting, although the method will be equally applicable if the grooves are not of the same extent, or when modified in other respects.

The main casting A is made with cores running the length of the casting, parallel to the axis of the cylinder, to leave four spaces F—F and G—G. Between these spaces there remains a web E which extends 60 from opposite sides of the cylinder interior in part circular form. These cores, therefore, leave the walls C—C of the cylinder, which are to be machined later concentric with the piston; and causing G—G to leave 65 a recess D, which is later to be machined to accommodate the outside or back of the slide valve. The web E is formed in the casting so that a boring tool used to form the seat D will be cutting metal throughout 70 its rotation, and will therefore cut or bore a true hole, which would not be the case if the tool had a one-sided cut, that is, cutting the metal only during part of its revolution. The cores are, of course, made of proper size 75 to allow for the machining of the surfaces and leave the web E of sufficient strength to support the strain and prevent any yielding of the boring bar.

As shown in Fig. 2, this web support of 80 the recess runs throughout the cylinder; while in Fig. 3 a modification is shown wherein E' is a frame work at the end of the cylinder, which may be put at either or both ends, and affords support for a collar or 85 guide for the boring bar. This arrangement is suitable when extreme accuracy throughout the length of the groove D is not necessary, but it is desired to insure accuracy close to each end of the cylinder. In either 90 case the web E or the frame E' is cut off after the slide valve recesses have been turned, bored or ground, and then the boring of the cylinder walls proper, to finish surfaces C—C is accomplished in any manner 95 desired. By this method it is possible to insure perfect accuracy and interchangeability 100 of the parts for cylinders of this design.

It will be seen that my method may be employed in other cases than the particular 105 adaptation shown and described, but

What I claim and desire to secure by Letters Patent is:

1. A method of making engine cylinders consisting of casting a cylinder with a tem- 110

porary guide wall forming a cutting support for a tool eccentric to the main cylinder bore, machining the eccentric bore, then cutting away the temporary supporting wall and finish boring the main cylinder walls.

2. A method of making engine cylinders having a recess cut in the inner wall and open to the cylinder proper, consisting of casting a cylinder provided with a temporary frame across the cylinder bore, using said frame as a guide for the boring or other machining tool to finish the surface of the recess in the cylinder, cutting away said frame and then machining the bore of the cylinder proper.

3. A method of making engine cylinders adapted to use a crescent-shaped slide valve, consisting of casting a cylinder by coring said cylinder to leave a substantially X-shaped temporary frame within the cylinder opening, utilizing said frame to guide a tool for machining the curved recesses in the inner wall of the cylinder, cutting out said temporary frame and finish machining the cylinder proper.

4. A method of making engine cylinders consisting of casting a cylinder with a temporary tool-supporting frame cast integrally therewith and having in the cross-section normal to the axis of the cylinder, a substantially X-shaped section, either half of said X-shaped section of frame being curved to form with the contiguous portion of the casting a circular guide of diameter slightly in excess of the radius of the cylinder, utilizing said temporary frame to guide in the

boring of recesses in the sides of the cylinder, cutting away said temporary frame, and thereupon finish-machining the main bore of the cylinder.

5. A method of machining a recess on the interior of a cylinder consisting in casting said cylinder with a web longitudinally thereof, adapted to hold and guide a tool while machining said recess, thereupon cutting away said temporary web and finish-machining the interior of the cylinder.

6. A method of machining a recess on the interior of a cylinder, consisting of including in the casting a portion of supplementary material with relation to the interior of the cylinder, whereby a tool will have its cutting edge engaging metal throughout its action, thereupon cutting away said supplementary portion of the casting and finish-machining the interior of the cylinder.

7. A method of machining a recess on the interior of a cylinder, consisting in including in the original casting a temporary portion adapted to support a tool while machining said recess, machining the recess, thereupon cutting away said temporary portion and finish-machining the interior of the cylinder.

In testimony whereof I have signed my name to this specification, in the presence of two subscribing witnesses, this 11th day of May, 1914.

MARTIN FISCHER.
